UNITED STATES PATENT OFFICE.

CHARLES W. DYSON, OF WASHINGTON, DISTRICT OF COLUMBIA.

WATER-TUBE BOILER.

1,279,094.

Specification of Letters Patent. Patented Sept. 17, 1918.

Application filed April 17, 1916. Serial No. 91,721.

To all whom it may concern:

Be it known that I, CHARLES W. DYSON, a citizen of the United States, residing at Washington, in the District of Columbia, 5 have invented certain new and useful Improvements in Water-Tube Boilers, of which the following is a specification.

My invention relates to water tube boilers and more particularly to one adapted for 10 marine work, and will be understood from the following description, taken in connection with the accompanying drawings, in which Figure 1 is a vertical longitudinal section; Fig. 2 a front elevation; and Fig. 15 3 a top view with certain of the parts removed and others broken away. Similar reference numerals indicate similar parts in the several views.

Referring to the drawings the numeral 20 1 indicates the front wall, and 2 the rear wall, of the setting. The boiler is shown with a furnace adapted for oil fuel, the openings in the furnace front for the burners or atomizers being indicated at 3 in Fig. 25 3. The furnace is shown as increasing in height from the front to the rear in a curve approximating that of the natural path of travel of the gases, thus giving the gases ample space in which to mix thoroughly and 30 to burn before entering the tubes forming the heating surface. By this arrangement an efficient combustion and a high furnace temperature is secured.

The tubes forming the heating surface are 35 divided into vertical sections, each section being made up of a series of tubes 4 expanded at their ends into corrugated wrought steel headers 5 and 6, the tubes being so disposed that laning of the gases is 40 prevented. The front headers 5 are inclined slightly from the front wall 1, and the rear headers 6 are disposed in a substantially horizontal plane near the roof of the setting and substantially in the plane of the water 45 level of the steam and water drum 7. By reason of this disposition of the headers, the tubes 4 extend in a straight line from the front headers 5 to substantially the mid-length of the tubes, and are then bent on 50 arcs having a substantially common center so as to enter the rear headers 6 at substantially a right-angle. The headers 5 and 6 thus lie in intersecting planes and the tubes are so bent that their ends are substantially normal to the planes of the two 55 sets of headers. As indicated in Fig. 3, each

corrugation or bend of the headers receives a group of four tubes, these tubes in practice being substantially two inches in diameter. Opposite each group of tubes is the 60 usual hand-hole fitting 8.

Extending across the front of the boiler, in the space above the tubes is a horizontal steam and water drum 7. The upper end 65 of each of the front headers 5 is connected to said drum by tubes 9, and the front end of each of the horizontal or rear headers 6 is connected to said drum by horizontal tubes 10. Each section is, therefore, provided with an independent inlet and outlet 70 for water and steam.

Placed across the bottom of the front headers, and connected thereto by nipples, is a box 11 which forms a blow-off connection 75 through which the boiler may be completely drained. This box is connected by groups of tubes 12 with the rear headers, and they support a roof baffle 13 extending from the cross-box 11 to the rear transverse baffle 14. The bank of water tubes is divided by the 80 baffles 14 and 14' into three transverse passes. A baffle 14' extends from baffle 14' to the rear headers 6 to direct the gases to the stack outlet. Access for cleaning any dust or soot 85 which may collect upon the baffle 13, in the space between said baffle and the lower part of the bank of tubes 4, may be had through the door 15.

The circulation of the water is through the nipple 9 shown in Fig. 1 and also 90 through the downcomers 16 shown in Fig. 2. The downcomers 16 shown in Fig. 2 conduct water directly from the steam and water drum 7 to the cross box 11, from which it is distributed through the front headers 5, 95 thus supplementing the water which reaches the lower tubes of the boiler through the nipples 9 shown in Fig. 1. The course of the gases is substantially that indicated by the arrows, namely, to the uptake ends of 100 the tubes, downward through the second pass and upward through the third pass, thence through the spaces between the tubes or nipples 10 to the stack outlet 17 between the inner ends of the rear headers and the 105 steam and water drum. The outlet is controlled by dampers 18.

Hinged to the framing at the front, are large doors 19 giving access to the hand-hole plates covering the tube ends. Doors 110 20 give access to the hand-hole coverings of the rear headers 6.

The advantages of my invention, which is especially adapted for marine work, flow from the decreased floor space for a given horse-power, the large furnace volume and the longer travel of the gases before they enter the water heating surface.

Any type of combustible may be used in the furnace.

While I prefer the individual header construction shown and described, my invention contemplates the use of water legs of the usual stayed-surface type in place of the headers.

It will be seen that the hot gases are first made to pass transversely over the uppermost ends of the tubes, at which point the tubes are inclined at the maximum angle to the horizontal, the upper part of each tube being, in fact, in a substantially vertical position. This leads to a decided advantage in inducing a maximum flow of water and steam through the tubes. Furthermore, the hand-hole fittings 8 of the rear headers and the expanded joints of the rear ends 25 of the water tubes, which approximately amounts to 50% of such joints in the boiler, are above or approximately at the water level. The advantage of this is that it is not necessary to empty the boiler to renew or tighten any of these joints.

What I claim and desire to secure by Letters Patent of the United States is:—

1. A water tube boiler having a bank of generating tubes curved for at least a part 35 of their length with their lower ends lying in a vertically extending plane and their upper ends lying in a horizontally extending plane, horizontally extending rear headers to which the upper ends of the generating tubes are connected, front headers to which the lower ends of the tubes are connected, a cross box connected to the lower ends of the front headers, water tubes connecting said box with the rear headers, a transverse steam and water drum above the lower ends of the tubes, substantially horizontal nipples connecting the inner ends of the rear headers to the steam and water drum, a stack flue leading upwardly from the space between the rear headers and the steam and water drum, and baffles to direct the flow of the gases over the tubes and through the nipples to the outlet.

and water drum, and baffles to direct the flow of the gases over the tubes and through the nipples to the outlet.

2. A water tube boiler having a bank of generating tubes curved for at least a part 55 of their length with their lower ends lying in a vertically extending plane and their upper ends lying in a horizontally extending plane, horizontally extending rear headers to which the upper ends of the generating tubes 60 are connected, front headers to which the lower ends of the tubes are connected, a cross box connected to the lower ends of the front headers, water tubes connecting said box with the rear headers, a baffle extending 65 from said box and supported on said water tubes, a transverse steam and water drum above the lower ends of the tubes, substantially horizontal nipples connecting the inner ends of the rear headers to the steam and water drum, a stack flue leading upwardly 70 from the space between the rear headers and the steam and water drum, and baffles to direct the flow of the gases over the tubes and through the nipples to the outlet.

3. A water tube boiler having tubes inclined upwardly from the front to the rear, headers to which said tubes are connected, the rear headers being set in a substantially horizontal plane, a transverse steam and water drum located at the front of the boiler in the space above said tubes, substantially horizontal nipples connecting the inner ends of the rear headers and the steam and water drum, nipples connecting the upper ends of the front headers with the steam and water drum, a cross box connected to the lower ends of the front headers, water tubes connecting said box with the rear headers and spaced apart from the main bank of tubes, 85 and down-comers from the steam and water drum to said cross box.

In testimony whereof I have hereunto signed my name in the presence of two subscribing witnesses.

CHARLES W. DYSÓN.
